(57) **CLAIM**

The ornamental design for a coffee maker as shown and described.

DESCRIPTION

FIG. 1 is a perspective view of a coffee maker in accordance with my design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom plan view thereof; and,

FIG. 7 is a top plan view thereof.

The broken lines shown depict portions of the coffee maker that form no part of the claim.

The orange lines represent portions of the coffee maker in which the design is embodied that form no part of the claimed design.

1 Claim, 7 Drawing Sheets
